UNITED STATES PATENT OFFICE.

GERALD S. JOYCE, OF GLOUCESTER, MASSACHUSETTS.

ELECTRIC-LAMP SOCKET.

1,102,757.

Specification of Letters Patent.

Patented July 7, 1914.

Application filed July 31, 1913. Serial No. 782,334.

To all whom it may concern:

Be it known that I, GERALD S. JOYCE, a citizen of the United States, residing at Gloucester, in the county of Essex and State 5 of Massachusetts, have invented certain new and useful Improvements in Electric-Lamp Sockets; and I do hereby declare the following to be a full, clear, and exact description of the invention, such as will enable others 10 skilled in the art to which it appertains to make and use the same.

This invention comprehends improvements in electric lamp sockets, and relates more particularly to the circuit closing 15 means therefor.

One of the objects of the invention is to provide an electric lamp socket, which will be extremely simple in construction, cheap to manufacture, artistic in design, and very 20 practical.

Another and more specific object of the invention is to provide an electric lamp socket wherein a rotatable annulus or ring is provided for making or breaking a circuit, through a pair of spring pressed plungers, or brushes, acting upon the inner side 25 of the ring.

With these and other objects in view, as will become more apparent as the description proceeds, the invention consists in certain novel features of construction, combination and arrangement of parts, as will be hereinafter fully described and claimed.

For a complete understanding of my invention, reference is to be had to the following description and accompanying drawings, in which—

Figure 1 is a side elevation of my improved socket, partly broken away and part 40 in section, and Fig. 2 is a horizontal sectional view.

Referring in detail to the drawing by numerals, 1 designates the preferably porcelain base, forming a part of my improved 45 socket. This base is inclosed in a suitable casing or shell 2 and is formed with a transverse recess into which is fitted a tubular member 3. This tubular member is formed of a suitable non-conducting material and 50 is divided centrally by a partition 4 into two sections. A metallic lining 5, in the form of a tube closed at one end, is placed within each of the sections of the tubular member 3. Wires 6 and 7 are connected 55 respectively to the linings 5 and form part of a circuit to be traced later. Plungers 8

and 9, of a suitable conducting material, slide within the linings 5 of the tubular member 3, and are forced outwardly by means of expansive spiral springs 10. 60

A ring, or annulus 11 revolves about the central portion of the base 1, and is formed with a plurality of notches 12 upon its inner edge. The outer edge of the ring is preferably knurled or roughened in any desired 65 manner so as to provide a good gripping surface. A wire 13 is embedded in the ring 11, which latter is formed of a non-conducting material, such as hard rubber. A plurality of lugs 14 are connected to the 70 wire 13 and extend inwardly therefrom so as to form contact members, said lugs alternating with the notches 12. Upon reference to Fig. 2 it will be seen that the inner edge of the ring 11 is cut away adjacent each of 75 the lugs 14 so as to form with said lugs a recess somewhat similar in shape to the notches 12.

An outer shell, or casing 15 incloses the inner shell 2 and the sleeve member 16, 80 into which an incandescent light is adapted to be screwed.

When the parts are arranged, as shown in Fig. 2, current may flow through the wire 6 to the corresponding metallic lining 5, 85 through this lining to the plunger 9, and from the plunger 9 through one of the lugs 14 and wire 13, to the corresponding lug 14. From this last mentioned lug the current flows through the plunger 8 and lining surrounding the same, to the wire 7, which may be connected to the sleeve 16, which engages 90 the base of the lamp. The current then flows through the filament of the lamp and back to its course through the return wire 95 17. It will be apparent that a rotation of the ring or annulus 11 in either direction will break the circuit by moving the plungers 8 and 9 from contact with the lugs 14. The plungers will seat in the notches 12 and 100 lock the ring against accidental movement.

From the foregoing description taken in connection with the accompanying drawing, it will be evident that I have provided a very simple, practical, and durable electric 105 light socket, wherein the circuit may be opened and closed by simply rotating a ring or annulus through a very slight arc.

While I have shown and described the preferred embodiment of my invention, it 110 will be understood that minor changes in construction and arrangement of parts may

be made without departing from the scope and spirit of the invention as claimed.

Having thus described my invention, I claim:

- 5 1. In an electric lamp socket, a base, a tubular member fitted within said base, spring pressed plungers slidable within the tubular member and insulated from each other, a rotatable ring surrounding the base, 10 the plungers bearing against the inner edge of said ring, and a plurality of electrically connected contact points formed upon said inner edge, a rotation of the ring causing the plungers to be engaged with, or disengaged from said contact points.
2. In an electric lamp socket, a base, a tubular member supported in said base, said tubular member being of a non-conducting material, a pair of metallic linings fitted 20 within the tubular member and spaced from one another, current conducting wires connected to said linings, spring pressed plungers movable within the linings, a ring rotatable about the base and engaged upon its inner edge by said plungers, and a plurality of electrically connected contact members carried upon the inner edge of said ring, a rotation of the ring causing the plungers to engage said contact members or to be disengaged therefrom.
3. In a device of the character described, a base, a tubular member fitted within said base and divided into two sections, a metallic lining fitted within each of said sections, a current conducting wire connected to each of said linings, spring pressed plungers operable within the linings and insulated from each other, a rotatable ring revolvable about the base, a continuous wire 35 embedded within the ring, and a plurality of contact lugs secured to said wire and adapted to be engaged by said plungers.
4. In an electric lamp socket, a base, a pair of spring pressed plungers operable 45 within the base and projecting beyond the periphery thereof said plungers being insulated from each other, a ring rotatable about the base and having notches formed upon its inner edge, a continuous wire em-

bedded within the ring, a plurality of contact members connected to said wire and opening upon the inner edge of the ring between the said notches, and means for connecting the plungers in circuit, a rotation of the ring causing the plungers to engage a 55 pair of said contact members, whereby a circuit is closed and a further rotation of the ring causing the plungers to engage in a pair of notches, whereby the circuit is opened.

5. In an electric lamp socket, a base, a ring rotatable around said base and longitudinally movable means coacting with the ring for making and breaking a circuit as the ring is rotated.

6. In an electric lamp socket, a base, a pair of metallic rods insulated from each other and projecting beyond the periphery of said base, a ring rotatable around said rods, and electrically connected contacts carried by said ring for simultaneous engagement with the rods.

7. In an electric lamp socket, a base, a pair of metallic rods carried by said base 75 and projecting laterally beyond the periphery thereof, said rods being insulated from each other, a ring revoluble around the base and engaging the extremities of said rods, a continuous conductor embedded in 80 said ring and contacts fixed to said structure and adapted to simultaneously engage the rods.

8. In an electric lamp socket, a base, a pair of spring pressed plungers operable 85 within the base and projecting beyond the periphery thereof, said plungers being insulated from each other, a ring rotatable about the base and engaging the extremities of said plungers and electrically connected 90 contacts carried by the ring for simultaneous engagement with the plungers.

In testimony whereof I affix my signature in presence of two witnesses.

GERALD S. JOYCE.
